UNITED STATES PATENT OFFICE

148,027

DESIGN FOR A GAME BOARD

David J. Karl, Hamden, Conn.

Application August 14, 1946, Serial No. 132,504

Term of patent 7 years

(Cl. D34—5)

To all whom it may concern:

Be it known that I, David J. Karl, a citizen of the United States, residing at Hamden, in the county of New Haven and State of Connecticut, have invented a new, original, and ornamental Design for a Game Board, of which the following is a specification, reference being had to the accompanying drawing, forming part thereof.

The figure is a face view of a game board, showing my new design. The board is of conventional thickness.

I claim:

The ornamental design for a game board, substantially as shown and described.

DAVID J. KARL.
